UNITED STATES PATENT OFFICE

HERMAN J. H. HUBER, OF UPPER DARBY, PENNSYLVANIA, AND CHARLES R. KELLOGG, OF SCOTIA, NEW YORK, ASSIGNEES TO GENERAL ELECTRIC COMPANY, A CORPORATION OF NEW YORK

EXPLOSION CHAMBER FOR LIQUID BREAK SWITCHES

Application filed April 25, 1929. Serial No. 358,089.

Our invention relates to electric switches of the type adapted to interrupt modern commercial power circuits. More particularly it relates to relatively large alternating current switches in which the contacts to more effectively extinguish the arc drawn therebetween are immersed in an insulating liquid and the initial separation thereof takes place within an explosion chamber. Inasmuch as the explosion chamber members of such switches must be capable of withstanding great internal pressure due to the sudden gas formation therein when the switch is called upon to interrupt a heavy load or short circuit it has been customary heretofore to construct the explosion chamber member of a metal having the requisite strength, such for example as steel or bronze. As the metal chamber member at its point of support has been in electrical connection with the fixed contact therein, the chamber member has been provided with a covering of insulation on both the inside and the outside to prevent the arc from whipping to the chamber walls. At the opening in the explosion chamber member through which the movable contact was withdrawn in the circuit interrupting operation of the switch, a special throat bushing of insulation has been provided which connected with the aforesaid insulation covering. With the ever increasing voltages at which electric power is being transmitted increasing difficulties have arisen in the interruption of those circuits. One of the problems which has given much trouble in the manufacture of these switches has been to prevent a breakdown of the insulation on the metallic explosion chamber member particularly at or near the throat bushing and the resulting establishment of an arc between the movable contact and the metal of the explosion chamber member. This difficulty has been especially pronounced in the case of switches employed on certain 220 Kv. transmission lines where under particular conditions of phase displacement or other disturbance the actual voltage to which the insulation is subjected is approximately double the already high line voltage. The object of our invention therefore is the pro-

vision of an electric switch having an improved explosion chamber member which shall overcome the problem of insulation breakdown mentioned above, and which shall also have the necessary mechanical strength to withstand the great pressures produced therein. 55

Our invention will be better understood from the following description taken in connection with the accompanying drawing, and its scope will be pointed out in the appended claims. 60

Referring to the drawing, Fig. 1 is an elevational view partly in section, of a switch embodying our invention; Fig. 2 is a detail drawn to a larger scale of the explosion chamber member; and Fig. 3 is a similar view drawn at a slightly smaller scale showing a modified form. 65

The switch which we have illustrated by way of example in Fig. 1 as embodying our invention has an enclosing casing comprising the steel tank 1 containing the insulating liquid, such as oil, in which the contacts are immersed and the cover 2 securely bolted to the tank and supporting the contacts, mechanism, etc. Through the cover 2 extend the insulator bushings 3, shown as of the oil filled type such as are usually employed on switches for the higher voltages. Secured to the lower end of each insulator bushing is the adapter 4 by means of which suitable adjustments may be made to compensate for variations in the bushings. Removably attached to the adapter is the fixed socket contact 5 and secured to the flange 6 of the adapter is the explosion chamber member or pot 7 hereinafter to be described. Between the two insulator bushings is the housing 8 containing parts of the operating mechanism including the connection to the contact operating rod 9. The lower end of this rod is secured to the cross head 10 which supports and connects the two contact rods 11. 85

In accordance with our invention we have overcome the insulation breakdown difficulties mentioned above when switches having insulated metallic explosion chambers have been used to interrupt high voltage circuits by providing for the switch an explosion 90

chamber member entirely of insulating material and constructed to have both the mechanical and the dielectric strength found necessary for such a member. As shown more clearly in Fig. 2 the explosion chamber member 7 has a tapering sidewall portion 12 which flares outwardly at its upper end to form the attaching flange portion 13 and which curves inwardly at its lower end to form the end portion 14 of the member. The explosion chamber member 7 we construct of built-up material composed of layers or laminations of paper or other suitable insulating material impregnated with a resinous condensation product and cured while subjected to the proper heat and pressure. We have found the well known phenol-formaldehyde type of resin to be a satisfactory condensation product for this purpose. The laminations extend continuously both circumferentially and longitudinally of the chamber member. As indicated in the cross section shown in Fig. 2 the laminations in the side wall portion are parallel with the inner and outer surfaces thereof and extend continuously therefrom into both the attaching flange 13 and the end portion 14. By this continuity we obtain great strength for resisting the intense bursting pressures which may be produced within the chamber when heavy loads or short circuits are interrupted by the switch. Centrally of the end portion 14 is the flared guide opening or throat 15 for the movable contact rod 11. The laminations, it will be seen, extend continuously from the side wall portion 12 into the end portion 14 to the throat 15, a separate throat bushing thereby being unnecessary. A greater length of the guide opening 15 is effected by building up that part of the end portion immediately surrounding the opening to a greater thickness. Likewise additional material in the attaching flange 13 and at the junction thereof with the side wall portions results in greater strength at these points. In Fig. 2 we have shown the explosion chamber member secured to the flange 6 of the adapter by means of a series of bolts 16 the heads of which engage the metal ring 17. The inner edge of this ring is curved to conform to the fillet between the side wall and the flange of the explosion chamber member and serves both to distribute the pressure of the bolt heads and to strengthen the member.

In the application of Charles F. Peterson, (Serial No. 358,072) filed concurrently herewith and assigned to the same assignee as the present application, there is disclosed and claimed a method and an apparatus with which explosion chamber members of the kind described above have been successfully made.

In the modification illustrated by Fig. 3 the explosion chamber member 20 is also of laminated insulating material, being similar in

construction to the previously described form. The securing flange in this form of our invention is in the form of an outwardly flaring conical extension 21 which is engaged by the securing ring 22 having a bevel inner face. Accordingly the metallic ring and not the conical extension 21 of insulating material is placed under tension due to high pressures generated within the explosion member 20. By means of the bolts 23 passing through the flange 6 of the adapter and the ring 22 the flange of the chamber member is securely clamped to the adapter. The flange 6 of the adapter in this case is provided with the inside backing rim 24 for the flared edge of the chamber member against which the edge is forced by the clamping ring, thereby producing a stronger joint at this point. That part of the end portion of the member surrounding the contact rod opening 15 differs slightly from the corresponding part of the previously described form in that it forms a depending lip 25 providing a somewhat longer tapering guide opening for the contact rod of the switch. In both forms of the explosion chamber member illustrated it will be noted that the attaching flange and the portion connecting it with the side walls are somewhat thicker than the side walls, thereby obtaining greater mechanical strength at that part of the structure. When found desirable that part of the structure may be strengthened still more by the substitution of canvas for paper to effect the additional thickness.

In accordance with the above description it will be seen that we have produced an electric switch having an explosion chamber constructed entirely of insulating material, thereby being devoid of all metal to which an arc may strike. The material of which we construct the explosion chamber member in addition to having a very high insulating value has by reason of the particular one piece laminated construction disclosed a maximum mechanical strength to resist the bursting pressures to which the chamber is subjected in service.

What I claim as new and desire to secure by Letters Patent of the United States, is:

1. In an electric switch having relatively movable contacts arranged to be separated in an insulating liquid, an all-insulation explosion chamber pot surrounding one of said contacts and having a throat opening through which a coacting contact is withdrawn when said contacts are separated, said explosion chamber pot being a one-piece structure composed of built-up laminations of insulating material extending longitudinally of and continuously throughout the wall structure of said pot so as to withstand high bursting pressures.

2. In an electric switch having relatively movable contacts arranged to be separated in

an insulating liquid, an explosion chamber pot immersed in said liquid and surrounding one of said contacts comprising a peripheral securing flange portion, a side wall portion 5 and an end wall portion having a throat opening through which a coacting contact is guided, said portions being continuous and forming a unitary structure composed of built-up laminations of insulating material 10 arranged so that the laminations of one portion extend into the adjacent portion or portions.

3. In an electric switch of the explosion chamber type, an explosion chamber pot having a unitary and continuous wall structure 15 comprising a tapering side wall portion terminating in an outwardly extending securing flange portion and in an end portion having a flared guide opening, said wall 20 structure composed of built-up laminations of fibrous material impregnated with a resinous condensation product arranged so as to extend longitudinally of said side wall portion and into said flange and end portions.

25 In witness whereof, we have hereunto set our hands this 23rd day of April, 1929, and this 20th day of April, 1929.

HERMAN J. H. HUBER.
CHARLES R. KELLOGG.
